UNITED STATES PATENT OFFICE

GEORGE A. BARKER, OF ROCHESTER, NEW YORK

PISTON

Application filed January 3, 1930. Serial No. 418,386.

(GRANTED UNDER THE ACT OF MARCH 3, 1883, AS AMENDED APRIL 30, 1928; 370 O. G. 757)

This invention described herein may be manufactured and used by or for the Government for governmental purposes, without the payment to me of any royalty thereon.

5 My invention relates to a piston and more particularly to a piston to be utilized in conjunction with those engines wherein lubrication of the piston and cylinder is brought about through the intermediary of the 10 "splash" system.

One object of my invention is to preclude "oil pumping" in an engine cylinder.

A second object is to bring about more effective cooling of the engine operating parts.

15 Another object is to facilitate the lubrication of an engine by affording an opportunity for cool oil to contact the engine parts.

Still another object is to prevent the formation 20 of carbon deposits on the internal surface of an engine piston.

Still another object is to provide a piston construction which operates to maintain a cooler operating temperature of that element and as a consequence avoid cracking or deterioration of the lubricant.

A cast iron piston head in an internal combustion engine obtains a temperature in the neighborhood of 850° F. and an aluminum head about 650° F. Oil thrown upwardly by 30 the rotation of the crank and coming in contact with this hot head has a tendency to "crack" and form a deposit on the lower side or in other words, on the inside of the piston. This formation of carbon adds to the weight 35 of one of the most important reciprocating engine parts. As the pistons especially in expensive engines are very accurately balanced naturally the formation of carbon thereon disturbs this balanced condition.

40 Furthermore as carbon is a very poor conductor of heat, oil thrown into contact with the before mentioned carbon deposit fails, to a large extent to accomplish its purpose, namely to cool the piston head. So serious an obstacle does this deposit present that it is maintained by some engineers that the piston will remain cool without the oil splash system.

In the present day engine construction oil after contacting with the hot piston has a

tendency not only to break up or lose its life but also to run down the piston skirt and be deposited upon the cylinder wall. This oil, which has obtained approximately the same temperature as the piston, on being deposited on the cylinder walls has a tendency to thin the lubricant already thereon with the result that an oil of inferior lubricating qualities becomes the normal lubricant for the piston and cylinder. This thin condition of the oil on the cylinder walls is further aggravated through its continual transfer between the said cylinder walls and the internal surface of the piston for as the piston descends it scrapes the lubricant from the cylinder walls and impels it upwardly along the internal surface of the piston skirt and on the ascent of the piston this same oil having assumed the piston temperature is returned by virtue of gravity and its own inertia to the cylinder walls. It is obvious that the continual interchange of the lubricant between the piston and cylinder has a very deteriorating effect on the same as well as adversely affecting the engine lubrication.

In present day engines rather elaborate rings are necessitated to effectively prevent "oil pumping" which the operating conditions heretofore described tend to facilitate. In other words the lubricant so heated with consequent lowering of its viscosity readily passes the common type of piston rings thereby entering into the combustion chamber of the engine with the consequent well understood deleterious effects.

To overcome the before mentioned operative difficulties I provide a piston with a series of ridges or projections on the inside and bottom edge of its skirt. The projections on the bottom edge of the piston skirt are so disposed and formed that they scrape excess oil from the cylinder walls and deflect it into the crank case and they also preclude lubricant coursing down the internal surface of the piston from contacting with the cylinder walls. The projections above those just mentioned are designed to preclude lubricant on the inside of the piston from ascending the inside walls thereof and contacting with the piston head and also cooperate with the said

projections on the bottom of the piston skirt to aid in returning lubricant directly to the crank case. I may also employ one or more grooves in the interior faces of the piston which grooves communicate by ducts or bleeders with the interior of the piston. These grooves operate effectively to prevent oil pumping.

In order that the invention may be more readily understood reference is had to the accompanying drawings forming a part of this specification and in which—

Fig. 1 is a combination of my invention with a splash system lubricated engine;

Fig. 2 shows one embodiment of my piston;

Figs. 3 to 8 illustrate various modifications of my piston construction.

An engine piston broadly designated as (1) is provided on its interior surface with a series of annular projections (2) having a lower side (2^a) normal to the piston walls and an upper side (2^b) at an angle thereto. Further projections (3) and (4) are provided on the base of its skirt. Peripheral grooves (5) are fashioned in the lower part of the exterior face of the piston and communicate through ducts or bleeders (6) with the inside of the piston. The construction is such that oil descending the interior surfaces of the piston is precluded through the intermediary of the projections (2) and (3) from engaging with the cylinder walls while surplus oil already deposited on the latter walls is removed by projection (4) upon the descent of the piston and deflected into the crank case by projection (3). Projections (2) through their specific construction prevent the upward movement of lubricant along the inside of the piston but facilitate downward passage thereof. These projections (2) also operate to project the lubricant back into the crank case without permitting all of it to traverse the piston on the lubricant's downward passage. Assisting projection (4) on the descent of the piston and similarly functioning to remove surplus oil on the ascent of the piston are grooves (5) which through the ducts (6) convey the oil they collect to the interior of the piston from which point it is immediately returned to the crank case by virtue of projections (2) and (3). These grooves (5) are fashioned with lips (5^a) and (5^b) to facilitate the removal of the said surplus lubricant on both the piston's ascent and descent.

It is obvious with this construction the time during which a particular quantity of lubricant is on the pistons and cylinder walls is a minimum with the result that cool oil from the crank case is better able to assume the burden of lowering the temperature of and lubricating the engine parts. With such a condition obtaining the formation of carbon deposits is inhibited as is also oil pump-

ing and the lubricating quality of the oil is not quickly impaired. Furthermore the projections on the piston operate to radiate heat therefrom and cooperate with the splash system to cool the cylinder and piston.

Having described my invention, what I claim as new and wish to secure by Letters Patent is:

1. In a cylinder, a piston having annular projections on its interior, each projection embodying a normal side and an angular side whereby lubricant deposited on the projections is precluded from ascending the internal surface of the piston.

2. In a piston having annular grooves on its exterior, ducts communicating the grooves and inside of the piston, projections on the piston interior adjacent the ducts, each of said projections having a normal side and an angular side whereby lubricant from the grooves and ducts is precluded from ascending the internal surface of the piston.

3. A piston having a groove on its exterior, said groove fashioned with upper and lower lips, annular projections on the inside of the piston and a duct communicating the groove with a point inside of the piston adjacent the projections.

4. A piston having a double lipped groove on its exterior, projections on its interior each having a normal and an angular side and a duct communicating the groove with a point inside of the piston adjacent the projections for the purpose described.

5. In a lubricated piston and cylinder, a piston having a double lipped groove on its exterior, a duct communicating the groove and piston interior and projections on the piston interior to preclude lubricant from the duct from ascending the inside wall of the piston.

6. In a lubricated piston and cylinder, a piston having a double lipped groove on its exterior, a duct communicating the groove and piston interior and projections on the piston interior to preclude lubricant from the duct from ascending the inside wall of the piston, each of said projections embodying a normal and an angular side for the purpose disclosed.

GEORGE A. BARKER.
